Primary Examiner — Mark Goodwin(74) *Attorney, Agent, or Firm* — Howard Russell(57) **CLAIM**

The ornamental design for a concrete reinforcement retaining chair, as shown and described.

DESCRIPTION

FIG. 1 is a top front perspective view of a concrete reinforcement retaining chair showing my new design;

FIG. 2 is a top right perspective view thereof;

FIG. 3 is a right side elevation view thereof, the left side elevation view being a mirror image thereof;

FIG. 4 is a front elevation view thereof, the back elevation view being a mirror image thereof;

FIG. 5 is a top plan view thereof; and,

FIG. 6 is a bottom plan view thereof.
